UNITED STATES PATENT OFFICE.

JOHN C. TRAPP, OF INDIANAPOLIS, INDIANA.

VALVE-GRINDING TOOL.

1,315,801.

Specification of Letters Patent. Patented Sept. 9, 1919.

Application filed September 11, 1918. Serial No. 253,507.

To all whom it may concern:

Be it known that I, JOHN C. TRAPP, a citizen of the United States of America, residing at Indianapolis, Marion county, Ind., have invented new and useful Valve-Grinding Tools, of which the following is a specification.

This invention relates to a power applying tool, especially for multiple adaptation.

10 This invention has utility when incorporated in a drive for grinding simultaneously a plurality of puppet valves into their respective seats.

Referring to the drawings:

15 Figure 1 is a fragmentary plan view of a Ford four cylinder internal combustion motor, with the cylinder head member removed and the grinder of this invention in position;

20 Fig. 2 is a view on an enlarged scale of the grinder tool in horizontal section just below the upper movable frame;

Fig. 3 is a bottom plan view of one of the valve engaging heads;

25 Fig. 4 is a fragmentary side elevation of the tool;

Fig. 5 is a front elevation of the tool, the handles being broken away;

30 Fig. 6 is a detail of the mounting of a valve engaging head; and

Fig. 7 is a bottom plan view of a head oscillating crank.

The motor block 1 having the cylinders 2 has the head member removably mounted 35 thereon by bolts engaging in the holes 3, the showing being of the Ford Motor Co., Detroit, Mich., motor as used in Model T automobile. However, in puppet valve types of multiple cylinder internal combustion motors 40 the general principle prevails, and only the slight proportioning of parts may usually be all that is necessary in adapting the device herein to the number of valves desired to be handled simultaneously and their 45 grouping.

Without the necessity of special machining, one of the bolts 4 mounting the cylinder head member in position on the block 1, may be remounted in position in the arm 5 for rigidly mounting a first frame having upright arm 6 in fixed position as to valve seats 7 in the member 1, for valves 8, having the diametrically spaced openings 9 in the top thereof.

55 These arms 5, 6, provide the first or main frame of the tool or grinder drive device.

The arm 6 carries at its upper extremity a pivot pin 10 as a fulcrum bearing for a pressure applying lever 11 of the second class. This lever 11, remote from the fulcrum bearing 10 has a handle 12. Intermediate the handle 12 and the fulcrum bearing 10, is ear 13 carrying pin 14 pivotally mounting tubular stem 15. Set screw 16 may serve as an adjustable holding device for a rod 17 in the 65 tubular stem 15.

This rod 17 passes through an arch brace member 18 and a main member 19 fast therewith, and these members of the second frame hold the rod 17 from longitudinal movement 70 relatively thereto by pins 20, 21. The rod 17 extends beyond this second frame and through the pair of parallel members 22, 23, held spaced from each other by the sleeves 24 about bolts 25. This third frame is held 75 mounted on the rod 17 by pin 26.

The member 23 of the third frame has guide openings 27 for tubular stems or sleeves 28. The sleeves 28 are provided with diametrical notches 29 upward from the lower 80 end. Pivot pins 30 hold for rocking in the notches 29 bars 31 provided with a pair of projections 32 for entering the openings or recesses 9 of the valves 8. These valve engaging heads mounted in the member 23 85 have centrally therein rods 33 provided with cross pins 34 coacting with the slots 29 above the members 31. Nuts 34' having upwardly open radial notches 35 are mounted on threaded portions 36 of the rods 33 on the 90 side of the member 22 away from the member 23, the rods 33 extending through openings 37 in the member 23 to align with the openings 27 in the member 23. The rods 33 are fixed against longitudinal movement as to 95 the member 22 by washers 38 and keys 39 on the side of the member 22 toward the member 23. Between the washers 38 and the sleeves 28 are disposed helical springs 40, normally independently yieldably urging each valve 100 engaging head away from the member 22, or axially downward to the limit as fixed by the pins 34.

The lever 11 may be considered as a link swingably carrying the second and third 105 frames as to the first or rigid main mounting frame.

The rods 33 extend upward through openings 41 in the member 19 of the second frame, thus maintaining the frames 18, 19, 110 and 22, 23, in a common plane. About the rods 33 are loosely mounted the driving

2

cranks 42 having upwardly overlapping ears 43 engageable by bars 44 for holding the cranks 42 in position adjacent the member 19. The bars 44 are mounted in position by bolts 45 which also assemble the members 18, 19 of the second frame. The cranks 42 are provided with projections 46 for engaging the notches 35 in the nuts 34' when moved into vicinity for such engagement by pressure on the handle 12 to overcome the action of spring 47 about the rod 17, which normally acts to maintain the second and third frames spaced from each other as limited by the pin 26. This pressure on the handle 12 for effecting driving engagement of the cranks 42 with the valve engaging heads also has the pressure of such applied power transmitted to hold the valves 8 against their seats 7 during the grinding operation.

The actuator effecting the oscillatory drive of the heads, is shown as having source in the reciprocable handle 48 having detachable universal joint connection 49 with angle lever 50 mounted by fulcrum pin 51 on the second frame. Short arm 51' of this angle lever 50, has a link 52 as a power transmitting means extending to link 53 connected to the plurality of cranks for driving the several valve engaging heads.

In operation, after the cylinder head member is removed and a bolt 4 is taken to mount the first frame 5, 6 rigidly in position, the projection 32 of the several heads 35 are properly engaged in the respective valves 8. The heads are readily locked in this valve engaging position, by moving the upper end of lever 54 outward away from the swingable frames, thus thrusting the bar 55 as guided by arm 6, through bracket 56, so that forked end 57 of the bar 55 engages the rod 17 just below the member 22, and as thus positioned may be a positive stop for taking the valve spring pressure for holding the valve and tool in position, while said springs 40 provide the pressure for the respective valves in grinding. Spring dog 58 holds the bar 55 in thrown or retracted position.

Oscillating or rather reciprocating of handle 48, with sufficient pressure applied to handle 12 to bring the projections 46 of the cranks 42 into the notches 35, effects a simultaneous back and forth turning of the several valves in the group of the tool engagement. After several such reciprocations of the handle 48, near the end of a stroke, the handle 12 may have the pressure thereon lessened, so that the spring 47 will effect disconnection of the drive from the valve engaging heads. A full stroke of the handle 48 to extreme position from this disconnection, with re-connection at such remote point by there applying pressure to

the handle 12, will shift the grinding region of each of the several valves in their oscillation. This stepping about of the valves as to their seats for the grinding, say by 60° changes, or more, is readily attained with all the advantages accruing therefrom in valve grinding. For inspection of the condition of the valves, it is not necessary to disconnect the first or main frame. The freedom of movement of the second and third frames is permitted over a wider range by withdrawing the bar 55, and with these second and third frames then swung free of the valves by the handle 12, full access to each of the valves 8 may now be had. The length of the stroke given the handle 48 may be such as is convenient for the operator, while the adjusting screw 16 permits such placing of the lever 11 as brings the handle 12 in a desired position for the holding of the clutch or driving connection in engagement.

In the idle movement of the handle 48 when shifting the connection of the drive or actuator to the several valve engaging heads, it is desirable that such heads not shift. Accordingly there is disposed pairs of levers 59 fulcrumed on the member 22 of the third frame and actuatable in pairs by intermediate springs 60 as frictional retarding means against the nuts 34'.

What is claimed and it is desired to secure by Letters Patent is:

1. A multiple drive device comprising engaging heads, a manually shiftable pressure applying lever, yieldable means for transmitting lever thrust to the heads, and a reciprocable actuator for the heads.

2. A multiple drive device comprising engaging heads, a pressure applying member effective for a plurality of heads, yieldable means for transmitting member thrust to the heads, a reciprocable actuator for the heads, and connecting means between the actuator and clutch heads permitting angular shifting of the actuator as to the several heads simultaneously to vary the region of reciprocation of the heads.

3. A multiple drive device comprising engaging heads, a pressure applying member effective for a plurality of heads, yieldable means for transmitting member thrust to the heads, a reciprocable actuator for the heads, and means for releasing the heads from the actuator.

4. A valve grinder tool comprising an engaging head, a rigid frame, a swingable frame connected to the rigid frame and carrying the head, means for locking the swingable frame against swinging when the head is in operative position, an actuator, and a pressure applying member for the head operable to clutch the actuator to drive the head.

5. A valve grinder tool comprising a frame mountable rigidly with a valve housing, a link extending from said frame, a frame swingably carried by the link, valve engaging heads mounted in the swingable frame, a reciprocable actuator for the heads, and a pressure applying member for the heads operable to clutch the actuator to drive the heads. 45
- 10 6. A valve grinder tool comprising a frame mountable rigidly with a valve housing, a link extending from said frame, a frame swingably carried by the link, independently yieldable valve engaging heads mounted in the swingable frame, a reciprocable actuator for the heads, and a pressure applying member for the heads operable to clutch the actuator to drive the heads. 50
- 15 7. A valve grinder tool comprising a plurality of valve engaging heads, and a common drive for said heads including a reciprocable actuator and a pressure applying lever for simultaneously clutching the actuator to the several heads. 55
- 20 8. A valve grinder tool comprising a frame mountable rigidly with a valve housing, a link extending from said frame, a frame swingably carried by the link, valve engaging heads mounted in the swingable frame, a reciprocable actuator for the heads, connecting means between the actuator and heads permitting angular relative shifting thereof, and a pressure applying member for the heads operable to clutch the actuator to drive the heads. 60
- 25 9. Mechanism for grinding a valve into its seat comprising a frame mountable rigidly with the valve seat, a link extending from said frame and provided with a pressure applying handle, a second frame connected to the link, a valve engaging head mounted in the second frame to have pressure from the handle applied thereto, and driving means for the head for turning the head as to the seat. 65
- 30 10. Mechanism for simultaneously grinding a plurality of valves into their respective seats comprising a fulcrum frame mountable rigidly with the valve seats, a lever extending from said fulcrum frame, a second frame to which pressure is applied by said lever, valve engaging heads carried by the second frame to be maintained by said pressure applying lever in operative engagement with the valves, and driving means independently of said lever for giving the heads an oscillatory movement. 70
- 35 11. Mechanism for simultaneously grinding a plurality of valves into their seats comprising a frame mountable rigidly with the valve seats, a lever fulcrumed on said frame and extending to provide a pressure applying handle, a second frame connected to the lever to have pressure applied thereto by said handle, valve engaging heads carried by the second frame, means for holding the second frame in position to maintain the heads in operative position as to the valves, and driving means for giving simultaneous oscillatory movement to the heads. 75
- 40 12. A valve grinder tool comprising a rigidly mountable frame, a pressure applying lever extending therefrom, a pressure transmitting frame pivotally connected to the lever, a third frame yieldably connected to the second frame, valve engaging heads independently yieldably mounted in the third frame, an oscillatory driving crank mounted on the second frame and having drive transmitting means extending therefrom, and lever pressure controlled engaging means for connecting the transmitting means to actuate the heads. 80
- 45 In witness whereof I affix my signature. 85
